UNITED STATES PATENT OFFICE.

OLE G. OLSEN, OF POMONA, CALIFORNIA.

ORCHARD HEATER.

Application filed January 21, 1925. Serial No. 3,810.

To all whom it may concern:

Be it known that I, OLE G. OLSEN, a citizen of the United States, residing at Pomona, in the county of Los Angeles and State of California, have invented a new and useful Orchard Heater, of which the following is a specification.

The object of this invention is to provide a simple means whereby a thorough combustion of the smoke and gases proceeding from an orchard heater or smudge pot may be effected, the device being so constructed that its constituent parts may be separated and telescoped to occupy small compass when the occasion for the use of the device has passed.

It is within the province of the disclosure to improve generally and to enhance the utility of devices of that type to which the invention appertains.

Although a preferred form of the invention has been delineated in the drawings, it will be understood that a mechanic, working within the scope of what is claimed, may make such alterations and changes as his skill may suggest, without departing from the spirit of the invention, or placing the utility of the device in jeopardy.

The invention will be best understood when the following specification is read in connection with the drawings, wherein Figure 1 shows in longitudinal section, a device constructed in accordance with the invention, parts remaining in elevation; and Figure 2 is a detail enlarged from Figure 1.

In Figure 1 of the drawings, there is shown an orchard heater including a fire pot 1 comprising a body 2 surmounted by a movable lid having a damper or the like, indicated at 4, and controlling the admission of air to the fire pot. The lid has a central upstanding circular collar 5.

The means for effecting a thorough combustion of the smoke and gases proceeding from the oil or other fuel burned in the pot 1, includes an inverted conical base 6, of circular outline, having a sleeve 7 resting on the lid of the fire pot about the collar 5. The base 6 is perforated as at 8, throughout the major portion of its area, the upper end of the base 6 being turned outwardly to form a depending circumferential flange 9.

The device includes a frusto-conical cap 10 which is imperforate, the cap being provided, near to its lower end, with a circum-

ferential, outwardly bowed bead 11 forming an internal seat 12. The bead 11 is spaced far enough from the wider end of the cap 10, so that said end of the cap forms an apron 14 which, preferably, is inclined outwardly at a more pronounced angle than the slope of the cap 10 above the bead 11. The base 6 and the cap 10 are made of metal which is stiff enough to withstand a high degree of heat, but resilient enough so that the flange 9 of the base 6 can be worked into seat 12 of the cap 10, as shown in the drawings. The cap 10 and the base 6 then are securely united, but, upon the application of some considerable force, the base and the cap may be separated from each other, and, then, the base 6 may be telescoped into the cap 10, so as to occupy but little space, when the occasion for the use of the device has passed, the base, of course, being detached, from the lid of the fire pot 1. Owing to the fact that the apron 14 slants outwardly at a more pronounced angle than the slant of the cap 10, the insertion of the flange 9 into the seat 12 of the bead 11 is facilitated.

In practical operation, air enters the base 6 through the perforations 8, and in the base 6 and in the cap 10, a thorough combustion of the gases and smoke proceeding from the fire pot 1 is effected. The result is the production of a high degree of heat and a minimum loss of combustible material when the fire pot 1 is in operation.

Having thus described the invention, what is claimed is:—

In a device of the class described, a frusto-conical cap communicating at its narrower end directly with the atmosphere, and provided, with an internal seat, the wider end of the cap being formed by an apron leading to the seat, the apron slanting outwardly at a more pronounced angle than the slant of the cap, and an inverted conical base having its wider end detachably received in the seat, the apron facilitating the insertion of the wider end of the base into the seat, and the base having perforations.

In testimony that I claim the foregoing as my own, I have hereto affixed my signature in the presence of two witnesses.

OLE G. OLSEN.
